UNITED STATES PATENT OFFICE.

ALFRED R. WOOD, OF BRIDGEPORT, CONNECTICUT, ASSIGNOR TO THE SINGER MANUFACTURING COMPANY, OF ELIZABETH, NEW JERSEY, A CORPORATION OF NEW JERSEY.

SAFETY DEVICE FOR SEWING MACHINES.

Application filed May 11, 1920. Serial No. 380,505.

To all whom it may concern:

Be it known that I, ALFRED R. Wood, a citizen of the United States, residing at Bridgeport, in the county of Fairfield and

5 State of Connecticut, have invented certain new and useful Improvements in Safety Devices for Sewing Machines, of which the following is a specification, reference being had therein to the accompanying drawings.

10 This invention relates to sewing machines, more particularly of the automatic type embodying stitch-forming mechanism and a work-clamp, with means for relatively moving them to sew a group of stitches, and with a stop-motion device for arresting the action of the machine at the completion of a group of stitches. Machines of the above type are customarily provided with a thread-20 cutter for severing the sewing-thread at the end of a sewing operation and with means for opening the work-clamp. If, as is usually the case, the path of movement of the thread-cutter intersects the needle path, it 25 follows that if the thread-cutter is operated at an inopportune time, breakage of the needle or thread-cutter blade will result.

Referring for example, to the Patent No. 30 885,310 of April 21, 1908, to Edward B. Allen, it will be seen that the lower thread-cutter and pull-off blades are mounted for movement across the needle-hole in the throat-plate and are connected to the clamp-opening treadle. If the operator depresses the treadle at any time prior to the elevation of the needle from the work after the formation of the last stitch of a group, breakage of the needle is almost certain to result.

Furthermore a premature opening of the clamp will release the work before the final stitch is set, thereby interfering with the proper action of the stitch-forming mechanism which is essential to the production of first class work. Operators in trying to obtain maximum production, are accustomed to depress the clamp-opening treadle at the instant the machine stops. Occasionally an operator, in anticipating the action of the stop-motion, depresses the treadle a fraction of a second too soon, thereby throwing

the pull-off and thread-cutter blades laterally against the needle which is on its last up-stroke and has not been raised clear of the work.

As a matter of fact, when the usual stop-motion device is tripped into action, the sewing needle is below the work and the main-shaft of the machine executes a half-revolution before its motion is finally arrested with the needle clear of the work. Although the time which elapses between the tripping of the stop-motion and the actual stoppage of the machine is very short, it frequently happens that an operator will depress the clamp and thread-cutter operating treadle during such period and will consequently damage the machine or spoil the product.

70 The primary object of the present invention is to provide a safety device for a sewing machine of the class described which will prevent the machine or its product being damaged by a premature actuation of the thread-cutter, work-clamp, or other part which is customarily actuated at the end of the sewing period.

More specifically, an object of the invention is to improve the machine shown in the 80 said Allen Patent No. 885,310 by equipping it with a safety device which will prevent the operator from lifting the work-clamp until the needle is lifted clear of the work on its last ascent and the machine has actually come to rest. The invention also contemplates the provision of means for preventing the starting of the machine while the clamp-opening and thread-cutter operating treadle is depressed.

90 To the attainment of the ends in view, a safety device, preferably in form of a shiftable stop or locking element, is positioned in the path of movement of an element of the clamp-opening or thread-cutting mechanism. This element is preferably so connected with the stop-motion device as to be automatically shifted to unlocking position after the machine is brought to rest.

100 Stop-motion devices commonly embody an eccentric stopping cam which is formed with a stop-notch into which a plunger carried by a tilting stop-motion lever is projected to arrest the action of the machine;

said plunger having been first moved by said lever into a position within the range of action of the stopping-cam. In order to defer the shift of the locking element to 5 unlocking position until after the needle has been raised clear of the work and the machine has stopped, the final movement of the stop-motion plunger into the notch of the cam is, through suitable connections, 10 made use of to shift the locking device from locking to unlocking position. A connection is also provided between said stop-motion lever and said locking element to prevent movement of said lever to running 15 position while the locking element is in work-clamp unlocking position.

A more complete understanding of the invention may be had from the following detailed description taken in connection with 20 the accompanying drawings in which Fig. 1 is a side elevation of a machine embodying the invention. Fig. 2 is a horizontal section through the bracket-arm standard at an elevation above the work-clamp and machine-bed. Fig. 3 is a bottom plan view of the machine. Fig. 4 is a fragmentary elevation of the present safety device and associated parts looking from the front end of the machine. Fig. 5 is a plan view of the 25 locking element and associated parts in the respective positions occupied during the sewing. Fig. 5^a is a similar view at a time in the sewing period when the stop-motion has been tripped to stop the machine, but before such stoppage has actually 30 been effected. Fig. 6 is a similar view at the end of the sewing cycle, after the machine has actually been stopped. Fig. 7 is a detail perspective view of an actuating 35 element which acts upon the locking element. Fig. 8 is a detail perspective view of the locking element, and Figs. 9 and 10 are views illustrating the cooperative action of the stop-motion plunger and stopping cam.

For the purposes of the present disclosure the invention is shown as embodied in a buttonhole sewing machine constructed substantially in accordance with the disclosure of the said Patent No. 885,310 and comprising a bed 1, standard 2, and an overhanging arm 3, terminating in the head 4 which carries the reciprocating and laterally vibrating needle 5, and the buttonhole-cutter 6. The needle 5 cooperates as usual 50 with the shuttle 7 to form stitches.

The work is clamped beneath the usual upper clamping-foot 8 pivotally carried at the forward ends of the arms 9 of the work-clamping lever 10 which is pivotally supported at 11 upon the hinge-block 11' fixed to a lateral extension of the longitudinal slide-plate 12. The longitudinal slide-plate 12 is mounted in suitable guideways in the transverse slide-plate 13 and each of such

plates is provided with the usual connection with the feed-cam 14 from which the respective longitudinal travelling and lateral shifting movements are derived.

The under-thread pull-off and cutter 70 customarily comprise a slide-bar 15 mounted in suitable transverse guide-ways upon the under side of the bed-plate 1 and herein shown as provided with an L-shaped spring-blade whose shank or stem 16 is attached 75 to the bar 15 by means of screws 17 and whose operative portion 18 is formed with a knife-edge adapted to contact yieldingly with the under side of the needle-throat of which the farther side of the needle-hole 80 19 forms with the same a cooperating member in conjunction with which the knife acts in shearing off the lower thread close to the material. The shank 20 of the pull-off lever is pivoted by means of a fulcrum-screw 21 to a fixed bracket 22 beneath the bed-plate and is provided intermediate its ends with a slot 23 entered by the shank of a screw 24 carried by the slide-bar 15. The contracted operative portion 25 of the pull-off lever is rounded upon its outer extremity and provided in its edge with a recess 26 for engagement with the lower thread leading from the thread-case to the needle-hole 19. The slide-bar has at one end of its lower side a stud 27 embraced by the forked forward end of a lever 28 mounted upon a fulcrum screw 29 and having its opposite end also forked to embrace the spherical head of a lateral stud 30 carried by the lower end of an arm 31 depending from a sleeve 32 loosely mounted upon the rock shaft 33 and carrying also a lateral arm 34 to which is attached a chain 35 which may be connected with a foot- or knee-lever within the convenient reach of the operator in charge of the machine.

As represented particularly in Figs. 1 and 2, the upper clamp member 8 is provided with the usual upper compound thread cutting and nipping blade 36 mounted upon the lower end of the vertical shaft 37 to which is fixed the crank-arm 38. The crank arm 38 is connected with one end of a rod 39 disposed in the direction of longitudinal movement of the work-holder and supported intermediate its ends by the arm 40 which is supported by the upper clamping arm 10 and serves in conjunction with the fixed collar 41 upon the rod 39 as a stop to limit the endwise motion of the rod under the action of the spring 42 connected at one end with the arm 40 and at the other end with a pin upon another fixed collar 42 upon the rod 39. The previously mentioned rock-shaft 33 is made use of to control the necessary endwise movements of the rod 39 for actuating the compound nipping and cutting blade 36. The rock-shaft 33 is mounted in bearings provided therefor 110 115 120 125 130

in a bracket 43 secured upon the bracket-arm 2, said rock-shaft having fixed to its forward end a lateral arm 44 carrying at its outer end a latch plate 45 pivotally mounted thereon by means of a screw pin 46 and carrying a lateral pin 47 engaged by the free end of a spring 48 having its fixed end attached to the arm 44 by means of a screw 49, whereby the inner end of the latch-plate 45 is yieldingly pressed against a lateral stop-pin 50 upon the arm 44 and the latch-plate is normally maintained in line with its carrying arm and with the rod 39. The rear end of the rock-shaft 33 is provided with a lateral arm 51 having a cylindrical socket 52 which carries a longitudinally-movable pin 53 with a collar 54 intermediate its ends and between which and the inner end of a perforated screw-plug 55 at the rearward end of the socket 52 is interposed a spring 56 for yieldingly maintaining the pin 53 in its forward position for engagement with the top of a collar 57 fixed upon the stop-motion plunger-rod 58 surrounded by a spring 59 interposed between said collar 57 and a bearing 60 for the plunger-rod in the tiltable stop-motion lever 61, whereby the plunger-rod is pressed normally upward for operative engagement with the stop-motion cam 62 mounted upon the hub of and having the usual yielding connection with the fixed pulley 63 upon the main-shaft 64, the stop-motion device herein represented being that of prior United States Patents Nos. 767,539 of August 16, 1904 and 806,231 of December 5, 1905.

When the stop-motion lever 61 is tilted forwardly to running position, as shown in dotted lines, Fig. 1, the upper end of the plunger-rod 58 is drawn out of the path of movement of the cam 62 and its fixed collar 57 is withdrawn from contact with the pin 53. The belt-guiding finger 65 carried by the lever 61 maintains the belt upon the fixed pulley 63 during the sewing. In the running position of the parts corresponding with the dotted line position of the stop-motion lever, the arm 44 is extended toward the axial line of the rod 39 and its latch-plate 45 rests yieldingly against such rod by which it is temporarily displaced from its normal position. As the work-clamp moves forwardly with the normal feeding movement communicated to it by the feed-cam 14, the rod 39 is carried with it and its end passes the latch-plate 45 which is thereby enabled to drop in behind it under the action of the spring 48. In the return feed movement of the work-clamp to initial position for the stitching of the second side of the button-hole, the rod 39 is detained by the latch-plate 45, while the upper thread-cutter carrying shaft 37 continues its travel with the clamp-member 8, whereby the angular relation of the crank-arm 38 and rod 39 is gradually changed and thus causes the compound cutting and nipping blade 36 to be slowly retracted toward the position shown in Fig. 2. The spring 42 is thereby placed under increased tension for the subsequent performance of its primary function.

When the stop-motion lever 61 is tripped at the end of the sewing operation it is tilted backwardly to bring the upper end of the plunger-rod 58 into operative engagement with the lower portion of the stop-cam 62, the continued rotation of which causes its higher portion to force downwardly the plunger-rod 58, Fig. 10, in performance of its usual braking action and to finally spring upwardly again into the stop-notch 66. The lateral movement of the plunger-rod 58 produced by the throw of the lever 61 brings the collar 57 into engagement with the yielding pin 53, as represented in Fig. 1, and the subsequent descent of the plunger-rod carries downwardly the collar 57 and permits the pin 53 to spring forward over the same and to be lifted upwardly thereby when the plunger-rod is projected into the stop-notch 66. The shaft 33 is thus rocked and causes the arm 44 with the latch-plate 45 to be lifted out of line with the rod 39 and the latter is permitted to move backwardly under the action of the spring 42 to produce the operative movement of the compound nipping and cutting blade 36 across the upper end of the needle-opening 19 through which the needle-thread extends from the work to the needle-eye.

The upper clamping foot 8 is preferably adapted to be lifted by means of the treadle operated mechanism for the lower thread-cutter. Connected to the arm 34 by means of the screw-pin 66 is the upper end of a bar 67 the cylindrically-shaped end of which enters a guide-aperture in a plate 68 screwed to the bed 1. Secured to the bar 67 by means of a screw 69 which passes through a vertical slot 70 in said bar is a bracket-piece 71 carrying a lateral roll 72 which is disposed above the rearward extremity of the upper clamp-arm 10. A pull upon the chain 35 will depress the bar 67 and force the roll 72 downwardly against the clamp-arm 10 thus tilting the latter to elevate the clamping-foot 8. In order to lock the lower thread-cutter mechanism and upper clamping arm during the sewing, a stop or locking element 8 is provided preferably in the form of a three-armed lever pivotally mounted by means of a screw 73 upon the plate 68. During the sewing, one arm 74 of said lever is yieldingly positioned below a collar 75 fixed to the bar 67. This arm serves to lock the bar 67 and arm 34 against depression by a pull upon the chain 35.

Another arm 76 of the stop element 8 carries a pin 77 which extends upwardly

through a slot 78 in the forward end of the link-bar 79 and is connected by means of a spring 80 to said link-bar. The link-bar 79 is connected at its rearward end to the stop-motion lever 61.

The third arm 81 of the stop-lever *s* is formed at its extremity with an undercut beveled face 82, Fig. 8, with which cooperates the beveled face 83 formed on the lever-plate 84 pivoted at 85 to the up-turned ear 86 on the plate 68. The lever-plate 84 is connected by means of a ball-and-socket joint 87 to the lower end of a two-sectional link 88, the parts of which are adjustable at 89 to vary the length of said link. At its upper end the link 88 is connected by a ball-and-socket joint 90 to the free end of a lateral arm 91 carried by a collar 92 fixed to the rock-shaft 33. While the machine is sewing, the stop 74 and link 79 occupy the relative positions shown in Fig. 5, the spring 80 being under tension.

In the position of the parts shown in Figs. 1 and 9, the machine has just finished the sewing and the needle is on its last up-stroke but is not clear of the work. The work-clamp lifting and lower thread-cutter operating mechanism is locked by means of the stop 74. The stop-motion lever has been tripped and has sprung to full line or stopping position. The collar 57 has shifted the pin 53 endwise against the force of the spring 56. The link 79 has been shifted from the position shown in Fig. 5 to that shown in Fig. 5^a, the slot 78 permitting such movement of the link 79 without disturbing the position of the stop 74 beneath the collar 75.

During the last half-rotation of the main-shaft from the position shown in Fig. 9, the plunger-rod 58 is depressed and the pin 53 is projected over the collar 57. After the needle has been lifted clear of the work, and the main-shaft has completed its last revolution, the stop-notch 66 is brought into register with the plunger 58 which thereupon is projected into said stop-notch to lock the machine. This action causes the collar 57 to lift the pin 53 and rock the shaft 33, thus depressing the arm 91 and link 88 and causing the lever-plate 84 to be turned from the position shown in Fig. 5^a to that shown in Fig. 6. During the latter part of this turning movement of the lever-plate 84, the beveled face 83 coacts with the similar face 82 on the arm 81 of the stop *s* to swing the latter, Figs. 5^a and 6, sufficiently to remove the stop-arm 74 from its locking position beneath the collar 75. The slot 78 in the link 79 permits the stop 74 to be swung by the lever-plate 84 to unlock the work-clamp. Therefore, the work-clamp and lower thread-cutter mechanisms are locked during the sewing and are not unlocked until the plunger 58 has been pro-

jected fully into the stop-notch 66 and the machine finally brought to rest at the completion of the last revolution of the main-shaft with the needle out of the work. The machine and its product are thus fully safeguarded against damage by a premature operation of the parts adjacent the sewing point.

When the machine is started, the shift of the stop-motion lever to dotted line position, Fig. 1, removes the collar 57 from beneath the pin 53, thus permitting the spring 93 to restore the shaft 33 and parts connected thereto to the positions which they normally occupy during the sewing. Also, the link 79 is drawn to the right, Fig. 1, and restores the stop 74 to the position shown in Fig. 5. If an attempt is made to start the machine while the work-clamp is held open, the collar 75 will block the motion of the stop 74 toward the rod 67, and the link 79 and stop-motion lever 61 will not be permitted to move to starting or dotted line position, Fig. 1.

It will be seen that the present construction provides for any desired adjustment of the clamp-lifting roll 72 on the bar 67, so that the clamping foot 8 need only be lifted sufficiently to release the work while the lower-thread cutting mechanism receives a full actuation in order that the proper length of bobbin-thread may be pulled off for the ensuing sewing operation.

The invention is not to be understood as limited to the exact construction shown and described as it is obviously susceptible of material modification both in the form and arrangement of its parts without departure from the invention.

Having thus set forth the nature of the invention, what I claim herein is:

1. A sewing machine having, in combination, stitch-forming mechanism, a work-clamp, a stop-motion device including a notched cam, a tilting stop-motion lever and a spring-pressed plunger carried by said lever and adapted to enter the notch in said cam to stop the machine, clamp-opening means, a stop-element for locking said clamp-opening means against operation while the machine is running, means connected to said plunger for shifting said stop-element to unlocking position, and a connection between said stop-element and said tilting lever for preventing movement of the latter to running position while the work-clamp is open.

2. A sewing machine having, in combination, stitch-forming mechanism, a work-clamp, a stop-motion device including a notched cam, a tilting stop-motion lever and a spring-pressed plunger carried by said lever and adapted to enter the notch in said cam to stop the machine, clamp-opening means, a three-armed stop-lever having one

of its arms adapted to lock said clamp-opening means against operation while the machine is running, means connecting a second arm of said three-armed lever to said plunger whereby motion of the latter into the notch in said cam will shift said three-armed lever to unlocking position, and a connection between the third arm of said three-armed lever and said tilting stop-motion lever for preventing movement of the latter to running position while the work-clamp is open.

3. A sewing machine having, in combination, stitch-forming mechanism, a work-clamp, a stop-motion device including a notched cam, a tilting stop-motion lever and a spring-pressed plunger carried by said lever and adapted to enter the notch in said cam to stop the machine, manually operated mechanism for opening said work-clamp, a locking element for preventing operation of said manually operated mechanism, means connected to said plunger for controlling the position of said locking element, and a link connected at one end to said tilting stop-motion lever and at its other end hav-

ing a limited yielding connection with said locking element.

4. A sewing machine having, in combination, stitch-forming mechanism, a work-clamp, a stop-motion device including a notched cam, a tilting stop-motion lever and a spring-pressed plunger carried by said lever and adapted to enter the notch in said cam to stop the machine, a rock-shaft connected to be operated by said plunger in entering the notch in said cam, a manually operated lever fulcrumed loosely on said rock-shaft, an endwise movable vertically disposed bar connected at its upper end to 40 said manually operated lever, guiding means for the lower end of said bar, a lateral projection on said bar adapted to engage and open the work-clamp, a stop adapted to engage said bar and prevent movement thereof to open the work-clamp, and means connected to said rock-shaft for moving said stop to ineffective position.

In testimony whereof I have signed my name to this specification.

ALFRED R. WOOD.
